(57) **CLAIM**

The ornamental design for a plastic fuel tank, as shown and described.

DESCRIPTION

FIG. 1 is a front perspective view of a plastic fuel tank, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof; and,

FIG. 8 is a front perspective view of the plastic fuel tank in another state.

The broken lines in the figures are for the purposes of illustrating portions of the plastic fuel tank, which form no part of the claimed design.

1 Claim, 8 Drawing Sheets
